Primary Examiner — Elizabeth J Oswecki(74) *Attorney, Agent, or Firm* — Berggren LLP(57) **CLAIM**

The ornamental design for a parcel terminal, as shown and described.

DESCRIPTION

FIG. 1 is a perspective view of a parcel terminal, showing my new design;

FIG. 2 is another perspective view thereof;

FIG. 3 is a front view thereof;

FIG. 4 is a back view thereof;

FIG. 5 is a side view thereof, the opposite side being a mirror image thereof;

FIG. 6 is a top plan view thereof; and,

FIG. 7 is a bottom plan view thereof.

The diagonal line shading shown in FIGS. 1-3 represents a transparent/translucent surface.
